Inventor

UNITED STATES PATENT OFFICE.

L. MYRON SLADE, OF BRIDGEPORT, CONNECTICUT.

EEL-STOP.

SPECIFICATION forming part of Letters Patent No. 256,394, dated April 11, 1882.

Application filed November 10, 1881. (No model.)

To all whom it may concern:

Be it known that I, L. MYRON SLADE, a citizen of the United States, residing at Bridgeport, in the county of Fairfield and State of Connecticut, have invented a new and useful Eel-Stop, of which the following is a specification.

My invention relates to improvements in eel-stops in which a plate is secured in a case or box immediately in front of the inlet from the street corporation cock of a main-supply pipe; and the objects of my invention are, first, to afford facilities for the regular flow of the water from the supply-pipe through the box or case to the service-pipe to prevent the eel from entering in the service-pipe; also, to provide a simple and inexpensive method for examining and cleaning the eel-stop. I attain these objects by the mechanism illustrated in the accompanying drawings, in which—

Figure 1 is a top view of the machine. Fig. 2, a vertical section; Figs. 3 and 4, detailed views of the stop-plate.

Similar letters refer to similar parts throughout the several views.

That others may fully understand my invention, I will particularly describe it.

The case *b* is a rectangular box of some suitable metal, and for the sake of cheapness and convenience it is cast in a single piece, excepting the removable side or cover *a*. On opposite sides the case *b* is provided with hubs *c*, threaded to receive the service-pipes *k k'*.

At the inlet side, *k*, the coupling-pipe is made short, so as to place the stop as near to the main service-pipe as possible, so that the eel, when he finds his progress arrested, may, without difficulty, withdraw into the main pipe again. Opposite and transverse to each of the openings to which the service-pipes are coupled I place a stop-plate, *g*, the edge of which extends nearly to the walls of the box or case *b*, and that part of said plate which is opposite the orifice approaches so close to the

part of the case surrounding said orifice that an eel will not be able to pass said plate. This distance will be determined by the cross-sectional area of the inlet-pipe, which must, as nearly as possible, equal the surface area

of an imaginary cylinder whose diameter equals the diameter of said orifice and whose length equals the distance between the plate *g* and the case *b* adjacent to said orifice. As the edges of the plate *g* exceed the peripheral dimensions of said orifice, they may be placed correspondingly nearer to the wall of the case *b*, and I therefore make said plates with an obtuse angle at about the center, as shown by dotted lines in Figs. 1 and 3. Thereby the inlet is contracted to admit a very thin sheet of water without retarding its velocity more than is due to the slightly-increased friction of an extended surface. The plates *g* are provided with ears *h h*, which enter into grooves *i i*, cast or otherwise formed in the interior surface of the case *b*, as shown, so that they require no further fastening. These ears extend beyond the edge of said plates, and thereby leave a passage for water all along the remainder of said edges. A central diaphragm or partition, *f*, with a central opening is also formed in the case *b*, to cause the currents to flow through the central part of said case and prevent accumulations of sediment.

The cover *a* is secured by screws *j j*, and may be easily removed when it may be necessary to inspect or clear out sediment or other obstructing matter which may have been carried into the case. When the cover has been removed the plates *g g* may be lifted out.

The service-pipes may be coupled by unions *d*, if desired.

Having now described my improvement, what I claim as new is—

1. The combination of the case *b*, having the internal grooves, *i i*, hubs *c c*, threaded to receive the service-pipes *k k'*, and the center plate, *f*, all cast in one piece, substantially as set forth.

2. The case *b*, combined with the stop-plates *g g*, set therein opposite, transverse, and close to the orifice of the service-pipes *k k'*, substantially as and for the purpose set forth.

3. The angular stop-plates *g g*, provided with the ears *h h*, combined with the case *b*, as described and set forth.

4. The combination of the case *b*, provided with hubs *c c* for connection with the service-

pipes, and the angular plates *g g*, set transversely to the orifice of said hubs with the re-entrant sides of said plates presented to said orifices, as set forth.

5. The combination of the case *b*, having the grooves *i i*, and the inlet *k* and outlet *k'*, with the angular plates *g g*, central dia-

phragm, *j*, and cover *a*, secured by the screws *j j*, all arranged substantially as described and shown.

L. MYRON SLADE.
